UNITED STATES PATENT OFFICE.

HARRY M. ESSINGTON, OF CHICAGO, ILLINOIS.

STORAGE-BATTERY LAMP AND MEANS FOR OPERATING SAME.

Application filed January 17, 1922. Serial No. 529,885.

To all whom it may concern:

Be it known that I, HARRY M. ESSINGTON, a citizen of the United States of America, and a resident of Chicago, county of Cook, 5 and State of Illinois, have invented a new and useful Improvement in Storage-Battery Lamps and Means for Operating Same, of which the following is a specification.

This invention relates mainly to vehicle 10 lighting devices and especially to storage battery lamps and to methods and means for using and operating same.

The main objects of the invention are to provide an improved form of lighting device adapted for use either as a flash light, hand lantern, or as a spot-light for an automobile; to provide such a manually portable lighting unit or lantern adapted for general use as an automobile accessory and having 20 a storage battery capable of ready charging in connection with the usual power equipment of the vehicle; to provide a tiltable mounting for the lantern adapted to facilitate its use in substantially the same manner 25 as an ordinary spot light; to provide contacts on said lantern adapted for battery charging connections, so arranged as to avoid any accidental short circuit when the lantern is removed from its socket and used 30 as a hand lantern; and to provide for ready renewal of parts and maintenance of the equipment.

An illustrative embodiment of this invention is shown in the accompanying drawings in which—

Figure 1 is a side view of the front part of a motor vehicle with part of the casing broken away.

Figure 2 is an enlarged side view of the lantern mounted in its spot light position with the near side of the supporting bracket or pocket broken away.

Figure 3 is a plan of the lantern mounted in its spot light position on the frame of the vehicle.

Figure 4 is a view of the back side of the lantern.

Figure 5 is a conventional circuit diagram of the lantern in its charging position, the wiring and apparatus at the left of the dotted line being in the lantern and that at the right being in or attached to the vehicle.

Figure 6 is a greatly enlarged fragmentary section on the line 6—6 of Fig. 4, and shows one of the resilient charging contacts.

In the construction shown in the drawings the portable light or lantern 1 is mounted removable in a socket 2 carried by the tiltably mounted arm 3. Said arm 3 is supported pivotally on the horizontal arm 4 which in turn is mounted to swing horizontally on pivot 4' of arm 4". Arm 4" is clamped rigidly to the upright frame member 5 of the motor vehicle 6. The lantern support or pocket member 2 is tiltable vertically and swingable horizontally by means of the handle 7, which is rigid with arm 3, for directing the spot-light when the lamp is in its normal position.

The lantern 1 comprises mainly a frame 70 or casing 8, an electric bulb or lamp 9, a reflector 9' therefor, a handle 10, a switch 11, and a pair of vertically disposed contact strips 12 arranged in slots 13 and connected in the circuit as shown in the drawings. Said contacts 12 are connected to the terminals of a small storage battery 14 mounted in the casing 8. The contacts 12 are set back in the apertures or slots 13 in the back of the casing 8 so as to be protected from danger of short circuiting such as might result from a metallic bar or wire being placed accidentally across the casing or as might result from standing the lantern with its back against a metallic object. 85

The pocket member or socket 2 has secured to the inner side of its back, 15 a pair of spring contacts 16 disposed vertically to register with the slots 13 and contacts 12 of the lantern 1. Each contact 16 is secured in place by and is electrically connected to a bolt 17 and said members are insulated by a bushing 18 and a back lining plate 19. In order to assure ample clearance for insertion and removal of the lantern, the socket chamber 20 is large enough to provide a small space 20' back of the lantern as shown in Fig. 2. This also gives forward and back play room for the forwardly acting springs 16 to operate effectively. The front of socket 2 is provided with a downwardly extending aperture or notch 8' to accommodate the forwardly projecting lamp and reflector and also permit ready removal of the lantern. 100

Referring to Figures 1 and 5, a switch 21 is mounted on the car dashboard to enable the attendant to connect the charging circuit at will. Closure of said switch 21 connects the lantern battery 14 to the gen- 110

erator 22 or to the vehicle battery 23 dependent upon the specific connections in the vehicle on which the lantern is used.

Referring to the contacts in the back of the lantern, as shown in Fig. 6, each contact 12 is fastened in place by a screw 24 to which the corresponding lantern wire is connected. The slots 13 in the back wall 8" of the lantern are lined with insulation 25. The wiring both for the lantern and for the vehicle may be of any form consistent with good wiring and fixture practice, as will be understood.

When the lamp is not to be used the switch 11 is opened. The contacts at the back of pocket 2 are always closed when the lantern is in place, but the charging depends furthermore upon whether or not the switch 21 is also closed.

In practical operation the lantern is used as follows: Normally it is kept in its spotlight position as shown in Fig. 1. As thus used it may be tilted either vertically or sidewise. If repairs are to be made after dark, as, for instance in case of a tire puncture, or if for any other reason a portable light is desired the lantern is removed by grasping the handle 10 and lifting the lantern out of its socket whereupon it may be used as any other lantern. It is then placed back in its socket and the battery recharged by closing the switches 16 and 21.

If the generator 22 be not running the bat-

tery 14 may still be charged from the vehicle battery 23, in which event the generator would, of course, be disconnected.

Although but one specific embodiment of this invention is herein shown and described, it is to be understood that numerous details of the construction shown may be altered or omitted without departing from the spirit of this invention as defined by the following claims.

I claim:

1. A lamp attachment for automobiles comprising a tilttable bracket secured to the automobile, and a manually portable lighting unit in the form of a lantern demountably secured to said bracket, said lantern having a storage battery, and means to supply current thereto when said lantern is mounted on said bracket.

2. A device of the character described comprising a casing, a handle thereon, an electric lamp mounted on said casing, a storage battery in said casing, outwardly facing contacts to receive charging current for said battery, and connections for said contacts, battery and lamp, said means including a pair of contact strips set in slots in said casing and back from its outer face to receive a pair of spring contacts connected to a charging source.

Signed at Chicago this 13 day of Jan., 1922.

HARRY M. ESSINGTON.
